LEATHER SPLITTING MACHINE

Stevenson A. Dobyne, St. Louis, Mo., assignor to
 Champion Shoe Machinery Company, St.
 Louis, Mo., a corporation of Missouri

Application August 7, 1930. Serial No. 473,572

6 Claims. (Cl. 69—13)

This invention relates generally to leather splitting machines and more particularly to a machine of that type having a reduction gearing between the operating device and its automatically adjustable feeding roll.

The object of the invention, generally stated, is to provide a leather splitting machine having adjustable feed rolls which are driven through a reduction gearing.

10 A further object of the invention is to provide a reduction gearing suitable for operating feed rolls which are adjustable relative to each other.

15 A more specific object of the invention is to provide a flexible connection between the operating device and the adjustable feed roll.

Other objects will appear to those skilled in the art when the following description is read in connection with the accompanying drawing, in which—

20 Figure 1 is a view in side elevation of a leather splitting machine constructed in accordance with my invention;

Figure 2 is an end view in section, taken along line 2—2 of Figure 1, showing the reduction gearing for driving the machine illustrated and the flexible connection which I have provided;

Figure 3 is a sectional view in end elevation taken along the line 3—3 of Figure 1; and

Figure 4 is a side elevation showing another embodiment of this invention.

Referring now to the drawing, and more particularly to Figures 1 and 2, the leather splitting machine comprises a framework consisting of a base 1, having a pair of upright members 4—5 at opposite sides thereof and a cross member 6 connecting the upper extremities of the upright members. Each of the upright members 4—5 is provided with a longitudinal slot 7, in each of which are mounted a pair of bearing boxes 8 and 9, which carry, respectively, the ends of shafts 10 and 11 upon which are mounted feeding rolls 12 and 13, respectively, the latter of which is corrugated. Upon one end of each of the shafts 10 and 11 are mounted gears 14 and 15, respectively, 45 which engage each other and co-operate to rotate the feeding rolls 12 and 13 simultaneously.

A gear housing 16 is mounted upon the framework and secured thereto by a plurality of bolts 17 disposed thereabout for maintaining it in rigid position relative to the frame. The housing 16 carries a pair of bosses 18 and 19, in the former of which is mounted a shaft 21 carrying at its inner end a pinion 22 and having provided at its outer end an operating device in the form of a 55 crank 23. Within the boss 19 is mounted a shaft 24, upon the inner end of which is mounted a gear 25 which engages and co-operates with the pinion 22 to operate the leather splitting machine, as will be more fully described hereinafter.

60 Between the gear 25 and the gear 15, is pro-

vided a flexible connection which in this particular embodiment consists in an arm 26 secured to the outer face of the gear 15, so that it rotates therewith. Upon the outer end of the arm 26 is mounted an axially extending pin 27 which is disposed for engagement with a slot 28 in the gear 25 and extending radially thereof, thus providing a variable eccentric connection between gears 15 and 25.

The bearing boxes 8 and 9, as previously stated, are slidable within the slots 7 and are adjusted to various positions by means of set screws 29 and a bar 30. The bar 30 thus controls the position of the roll 12, and only by movement of the bar 30 can the position of the roll 12 relative to the frame be changed. On the other hand, the set screws 29 merely operate to regulate the force of the springs which support the roll 13, as will be more fully described hereinafter.

The base 1 is provided with a plurality of laterally extending lugs 31, arranged in vertically aligned pairs and in alignment with the upright members 4 and 5. A plate 32, having cylindrical portions 33 at each end thereof, is attached to the framework, with one of the cylindrical portions 33 interposed between each pair of lugs 31, whereby to form guide cylinders.

Within each of the cylinders 33 is provided a spring 34, which is engaged at its lower end by a head 35 slideable relative to the cylinder and having therein a conical recess 36, as clearly illustrated in Figure 1, for the reception of the pointed end of the set screw 29. One of the set screws 29 is in threaded engagement with the lower lug 31 of each pair, so that the position of the head 35 may be varied by adjustment of the screw 29.

The spring 34 is engaged at its upper end by a head 37 which is also slideable within the cylinder 33 and which is mounted upon a stem 38 engaging at its upper end the bearing box 9, whereby a rigid connection between the bearing box 9 and the head 37 is provided, through which the force of the spring 34 is transmitted directly to the bearing box 9. This organization is, of course, to be found in duplicate on opposite sides of the machine. A pair of springs 40 are interposed between the bearing boxes 8 and 9 on each side of the machine, as clearly illustrated in Figures 1 and 3, and provide a yieldable connection for the transmission of force between the bearing boxes. It is apparent that the springs 34 and 40 are counter to each other, thus providing a strong but yieldable mounting for the roll 13.

Each of the bearing boxes 8 is provided with a pair of upstanding ears 42, which carry a cross pin 43 extending across the gap therebetween. The top piece 6 of the framework is provided with a slot 44 for the accommodation of the slide bar 30. A hand lever 45 is pivotally mounted upon the top piece 6 at its central portion by a bolt

46, which is provided with a wing nut 47 disposed to be tightened and thereby restrain movement of the hand lever 45 relative to the top piece 6. The hand lever 45 is provided at its 5 lower end with an open slot 48 for engagement with a pin 49 carried by the slidable bar 30, whereby is established a connection which permits the operation of the slidable bar by the hand lever 45. It will be noted that the slidable bar 10 30 is provided at each of its ends with inclined surfaces 51, which surfaces lie in parallel planes and are disposed for engagement with the transverse pins 43 carried by the ears 42 of the bearing boxes 8. It will thus be seen that when the bar 15 30 is actuated to the left by the hand lever 45, a downward force is applied to the bearing boxes 8 through the pin 43 to move them downwardly against the action of the springs 34 and 40.

A splitting knife 52 is carried by brackets 53, 20 which are connected to each of the upright members 4 and 5, and has its cutting edge disposed adjacent to the space which intervenes between the feed rollers 12 and 13. Upon the opposite sides of the upright members 4 and 5 is mounted 25 a working table 54, which facilitates in guiding the leather to be split.

An indicating scale is provided on the bar 30, which co-operates with the pointer 55 to indicate the position in which the upper feed roller 30 12 is stationed.

In the operation of the device, the set screws 29 are actuated to move the lower roller 13 to a position in which its top is just even with the cutting edge of the knife 52 and the bar 30 is then 35 operated until the desired position is shown at the indicator, and in which position the upper feed roller will be disposed so that the thickness of the leather, after passing the cutting edge of the knife, will be such as is desired. It is thus 40 seen that the graduated scale on the bar 30 indicates the distance between the bottom of the upper feed roll 12 and the cutting edge of the knife 52, which distance determines the thickness of the sheet after the splitting operation is 45 completed.

When the desired adjustment between the feed roller 12 and the knife edge has been attained, the handle 23 is operated to drive the rollers through the gear train hereinbefore described 50 and through the flexible connection 27-28. The flexible connection permits the relative adjustment between the bearing boxes 9 and the framework to which the gear housing 16 is rigidly attached and, accordingly, permits of a variation 55 in the radial distances between the axes of the gears 15 and 25, as well as between the axis of the pinion 22 and that of the gear 15, during such adjustment of the bearing boxes 9.

In the embodiment shown in Figure 4, the 60 flexible connection 27-28 is substituted by an Oldham coupling 56, wherein a pair of co-operating members are each provided with a groove and tongue perpendicular to each other and which operate in a manner well known in the art.

By the use of such a flexible connection 65 between the gears 15 and 25, it is possible to permit movement of the roll 13 relative to the frame and roll 12 without altering the position of the driving gear and casing. It is thus possible to rigidly 70 connect the casing of the driving gear to the frame and thereby obtain a steady and positive support for operating the crank.

From the foregoing description, it is believed that a preferable embodiment of my invention has been fully described, but it is to be understood that this disclosure is merely illustrative and that many modifications will present themselves to those skilled in the art, which may be made without departing from the spirit of my invention or from the scope of the appended claims. 80

Having thus described the invention, what is 85 claimed is:

1. A device of the kind described comprising, a frame, a pair of rolls adjustably mounted in co-operative relation on said frame, interconnecting gears secured to each of said rolls, one of which gears is connected to drive the other, driving mechanism journaled upon a rigid part of said frame, a flexible driving connection between said mechanism and said driving gear, and means for adjusting the rolls relative to the frame. 95

2. In a machine of the character described, a pair of parallel feed rollers one of which is mounted for movement toward and from the other, interconnecting gears, one on each of said rollers, the gear on said movable roller being adapted 100 to drive the other, a driving shaft for operating said movable gear, and connections between said shaft and said movable gear movable to permit substantial variation in the axial distance therebetween. 105

3. In a machine of the character described, a pair of parallel feed rollers, means for mounting one of said rollers for movement relative to the other, gears on said rollers meshing with each other, the gear on said movable roller being 110 adapted to drive the other, a drive shaft journaled in a fixed mounting, and a flexible driving connection from said drive shaft to said movable roller automatically shiftable to accommodate variations in the distance between the axes of 115 said drive shaft and said movable roller.

4. In a machine of the character described, a frame, a pair of parallel feed rollers, means for mounting one of said rollers for movement on 120 said frame relative to the other, connections 120 whereby said movable roller drives the other roller, a drive shaft journaled in a fixed bearing on said frame, and driving connections from said shaft to said movable roller having an extensible portion adapted to accommodate variations in the 125 distance between the axes of said drive shaft and said movable roller.

5. In a machine of the character described, a frame, a pair of parallel feed rollers, means for mounting one of said rollers for movement on 130 said frame relative to the other, a drive shaft journaled in a fixed bearing on said frame, and driving connections from said shaft to said roller including a crank on one having a sliding connection with the other adapted to accommodate 135 variations in the distance between their axes.

6. In a machine of the character described, a frame, a pair of parallel feed rollers, means for mounting one of said rollers for movement on 140 said frame relative to the other, a drive shaft journaled in a fixed bearing on said frame, and driving connections from said shaft to said roller including a crank on one having a pin-and-slot connection with the other adapted to accommodate 145 variations in the distance between their axes.

STEVENSON A. DOBYNE.
